UNITED STATES PATENT OFFICE.

JOHN EDWARD FRIEND, OF GAWLER, SOUTH AUSTRALIA, ASSIGNOR TO
JAMES MARTIN, OF SAME PLACE.

HYDROCARBON-MOTOR.

SPECIFICATION forming part of Letters Patent No. 550,785, dated December 3, 1895.

Application filed February 9, 1893. Serial No. 461,601. (No model.) Patented in England February 6, 1893, No. 2,596.

To all whom it may concern:

Be it known that I, JOHN EDWARD FRIEND, engineer, a subject of the Queen of Great Britain and Ireland, formerly residing at 5 Auckland, in the British Colony of New Zealand, but at present residing at Gawler, in the British Colony of South Australia, have invented an Improved Hydrocarbon-Motor, (for which a patent has been obtained in England 10 with my consent by John Charles Lanyon through a communication to him from my assignee, James Martin, of the firm of Martin & Company, Limited, of Gawler, South Australia, dated February 6, 1893, No. 2,596,) of 15 which the following is a specification.

My invention has relation to gas or vapor engines; and it has for its object certain improvements whereby the efficiency and durability of the engine are materially increased 20 and whereby its function is rendered more uniform and reliable, as will now be fully described, reference being had to the accompanying drawings, in which—

Figure 1 is a sectional elevation of a double-cylinder motor constructed according to 25 this invention. Fig. 2 is a sectional plan thereof. Fig. 3 is a sectional elevation of a single-cylinder motor, showing the hydrocarbon-vaporizer in the bed-plate. Fig. 4 is a 30 plan of a pair of double cylinders, showing the pipe and valve attachments. Fig. 5 is an end view of the pair of double cylinders, showing section of throttle-valve and arrangement and construction of admission and passover 35 valves. Fig. 6 is a sectional plan of a single cylinder, showing valve and pipe attachments. Fig. 7 is a cross-section of a single cylinder, taken through the combined admission and throttle valves.

Referring more particularly to Figs. 1, 2, 4, and 5, in which I have illustrated my invention in its application to a twin-cylinder engine, it will be seen that the cylinders A A' have two interior diameters and are closed at 45 each end by suitable heads a and a', respectively. The smaller ends of the cylinders through which the combustion-chambers of the pistons move are jacketed, the annular space between the cylinders being divided by 50 suitable partitions or ribs into three annular spaces or passages d, d', and II. The passages

II communicate with the interior of their respective cylinders through the medium of admission-ports h, the passage II of cylinder A being in communication with the outlet side 55 of a casing G for a check or back-pressure valve, while the passage II in cylinder A' communicates with the outlet side of a casing G' for a check or back-pressure valve, the inlet side of said valve-casings G and G' being connected through pipes or ducts F and F', respectively, with the outlet side of a valve-casing E, containing two admission or pass-over valves e and e'. (Shown in dotted lines in Fig. 5.) The annular passages d' of the 60 two cylinders A and A' are in communication with the outlet side of valve-casings K and K', respectively, for air-admission valves and with a duct or passage d', Fig. 2, which passage d' is in communication with the inlet 65 side of the casing D for the main admission or throttle valve D', Fig. 5, while the passages d communicate, like passages d', with the outlet side of valve-casings L and L', respectively, said casings containing each an air-admission valve, and with the interior of the smaller end of their respective cylinders through exhaust-ports I, and with the inlet 70 side of a valve-casing for an exhaust-valve I', Fig. 1.

The inner larger ends of the cylinders A and A' communicate with valve-casings C and C' on one side of the admission-valves e and e', respectively, contained in said casings and shown in dotted lines in Fig. 5, the said casings communicating with the outlet side of the casing D for the main or throttle valve D' by a three-way pipe D', Fig. 5. The throttle-valve casing is further connected through a gas or vapor supply pipe d'', Fig. 2, leading 85 to suitable distributing-passages d''' in said valve-casing with a source of gas or vapor supply—as, for instance, with a vaporizer R, located adjacent to or on bed-plate of the engine, Fig. 3.

The pistons B and B' for cylinders A and A' are of the hollow type, having two heads b and b', respectively, fitting the smaller and larger diameters of their respective cylinders, the piston-rods M of said pistons being connected by rods N with the crank-shaft O. As will be seen, the hollow pistons constitute the 95 100

combustion-chamber and are of such diameter relatively to the smaller diameter of their respective cylinders as to leave an annular space or passage d^3 between them and the inner wall of such cylinders. The inner or larger piston-heads b' perform the function of pump-plungers, for purposes presently explained.

The operation of the described engine is as follows: Assuming the various parts to be in the position shown in Figs. 1 and 2, and, further, assuming that the engine has been at work, the air in passage d being heated by heat radiated from the cylinder and combustion-chamber, and that a charge of hot air and gas is contained in the larger end of cylinder A' in front of its piston, then if the crank-shaft O revolves in the direction of arrow on fly-wheel, Fig. 1, the piston of cylinder A' will move forward, forcing the charge into passover-valve casing E, thence through pipe or passage F, check-valve casing G, passage H, and inlet-ports h into the smaller end of cylinder A. During this forward movement of the piston B air is drawn into passages d and d' , and as said piston uncovers the exhaust-ports I the air in passage d or air and waste gases and products of combustion behind the piston are expelled through exhaust-ports I and exhaust-valve I', while air is drawn into passage d' through port in air-valve casing K'. As the piston B' commences its forward movement, the piston B commences to move backward, drawing in a charge of hot air and gas or vapor through valve-casing C and meeting, receiving, and finally or fully compressing the charge of hot air and gas or vapor forced into its combustion-chamber by piston B', at the same time drawing air into space d' through casing L for one of the air-admission valves, while the air-admission valve for casing K is closed, and as soon as the piston B reaches the limit of its backward motion the charge of hot air and gas, being then fully compressed, is ignited by any desirable or well-known means, which I have deemed unnecessary to illustrate, the explosion of the charge driving the piston B forward, while piston B' moves backward, the described functions of said pistons being now reversed.

From the above description it will be seen that I obtain two impulses at each complete revolution of the crank-shaft. On the other hand, the combustion-chamber and the outer smaller portion of the cylinder are kept at a comparatively-low temperature, while the radiated heat is utilized to a very great extent in heating the air drawn into space d' , afterward combined with a gas or vapor. Furthermore, the arrangement of the valve system is such that the hot air and gas or vapor are simultaneously drawn into a valve-casing, wherein they commingle before being drawn as an explosive charge into the forward end of one of the cylinders. The forcible expulsion of the charge from the forward end of one cylinder into the rear end of the other results not only in a partial compression, but also in a further and more intimate admixture or commingling of the air and gas or vapor, thereby increasing the explosive effect.

I will now describe my invention in its application to a single-cylinder engine, reference being had to Figs. 3, 6, and 7, the same letters of reference being used to indicate like parts.

The cylinder A is shown as of three interior diameters, the piston B having three piston-heads b b' b^2 , said cylinder being open at its inner end and provided with the air-passages d and d' , air-admission-valve casings L K in communication with said passages, exhaust-valve casing and valve I' in communication with passage d , and passage d^3 in communication with passage d through exhaust-ports I. In this construction I combine the throttle and admission valve C D, Fig. 7, adapted to admit a charge of hot air and gas to the forward end of the cylinder A in rear of the outer or larger piston-head b' , whence such charge is forced by the piston through pipe or passage E, check-valve casing G, passage H, and admission-ports h into the rear end of cylinder A. The piston B is directly connected with the crank-shaft O by means of a connecting-rod N in a well-known manner.

In Fig. 3 I have illustrated a vaporizer or vapor-producer, consisting of a suitable vessel R, along the bottom of which is arranged an air-pipe P', having a vertical branch P² extending outside of the vessel and being provided with an air-valve casing P of any suitable construction, a vapor-pipe d^2 , opening into the top of the vessel R, being connected with the admission-valve casing at R', Fig. 7. The air-pipe P' is of course a perforated pipe, and in order to prevent hydrocarbon in a liquid state being drawn off with the vapor or gases I place over the pipe, preferably on a perforated supporting-plate, a suitable filter-bed advantageously composed of layers of pumice-stone or other similar porous or spongy material alternated with layers of wool.

I will now describe one complete cycle of movements as performed by the single-cylinder motor, as shown in Figs. 3, 6, and 7.

Assuming the various parts to be in the position shown in Fig. 3, then if the crank-shaft O is turned around in the direction indicated by the arrow on the fly-wheel the large end of the piston B in the cylinder A travels forward and draws in a charge of mixed hydrocarbon gas and hot air through the combined throttle and admission valves C, which are in direct communication with the air-valve and air-passage d and the hydrocarbon vapor or gas outlet pipe d^2 on vaporizer, the hot air and gas meeting and mixing within the throttle-valve casing. On the return stroke of the piston the charge of gas and air contained in the cylinder between the large

- head b of the piston and the middle head b^2 is compressed and forced through the delivery-pipe E and the back-pressure valve G into the combustion-chamber of the piston.
- 5 When the piston has traveled back to the position shown in Fig. 6, ignition takes place and the exploded gases expand, causing the piston to move forward and by means of the connecting-rod N give motion to the crank-shaft O, thus completing the cycle of operations and obtaining one explosion or impulse for every complete revolution of the crank-shaft. The center piston-head b^2 , during its reciprocating motion, forms a wall for the prevention of the escape of the mixture of gas and air into the exhaust-chamber, during the period of compression, and also performs the functions of a pump-plunger, whereby cold air is drawn into the cylinder through the air-valve L for the purpose of cooling the walls of the cylinder and combustion-chamber and is forced out through the exhaust-ports I and exhaust-valve I', while the outer piston-head b performs a like function in respect of passage d and draws air into the same through air-valve casing K, such air being used for admixture with gas or vapor, as hereinbefore set forth.

The engine-frame or bed-plate P contains the vaporizer, and its operation is as follows: When the large end of the piston B travels forward, it draws atmospheric air in through the air-valve P, down through the pipes P P², and after the air has percolated through the filter-bed in the box R it is drawn through the outlet-pipe d², as a saturated gas or vapor, into the throttle-valve, where it mixes with the hot air, as before described.

The vaporizer is shown in Fig. 3 as formed in the bed-plate; but it may be a separate chamber, if desirable.

The operation of the motors, as herein described, in conjunction with a vaporizer, can be performed in a similar manner without a vaporizer, where the use of coal-gas or other prepared hydrocarbon gas is preferred.

Having thus described my invention, what I claim as new therein, and desire to secure by Letters Patent, is—

- 50 1. In a twin cylinder motor comprising parallel cylinders having different interior diameters, pistons having corresponding heads, the valve casings G and G' containing each a check valve, the valve casing E divided into two chambers each containing a check valve, the pipes F and F' connecting the valve casings G and G' with the chambers in casing E on the outlet side of the valves therein, ducts connecting the larger of the cylinders with said casing E on the inlet side of its valves, the main admission or throttle valve casing, and valved passages connecting the larger end of the cylinders with the outlet side of said casing whereby a charge of explosive fluid supplied to the larger end of one cylinder is forced into the smaller end of the other, substantially as and for the purpose set forth.
2. A gas or vapor motor comprising a cylinder of different interior diameters provided with an annular passage surrounding the outer end or portion of least diameter of such cylinder, and an air admission valve casing communicating with said passage, in combination with a main admission or throttle valve casing whose inlet is in communication with said annular passage, a gas or vapor supply pipe connected with said inlet of the throttle valve casing, and a suction device adapted to draw the air from said annular passage into the throttle valve casing, for the purpose set forth. 70
3. A gas or vapor motor comprising a cylinder of different interior diameters, a piston provided with heads fitting the different cylinder diameters, an annular passage encompassing the portion of least diameter, ports connecting the said passage with the interior of the cylinder, and an exhaust valve casing whose inlet is connected with said annular passage, for the purpose set forth. 85
4. A gas or vapor motor comprising a cylinder provided with two valve controlled air passages and a passage for motive fluid, said passages encompassing the combustion chamber of the cylinder, ports connecting one of the air passages and the motive fluid passage with said chamber, and an exhaust valve casing in communication with the combustion chamber through one of said air passages and its ports, in combination with a casing for a distributing valve having its inlet connected with the other air passages and with a source of gas or vapor supply, and a suction and forcing device adapted to draw air from said air passage and gas or vapor from its supply passage into the distributing valve casing and from the same into the combustion chamber of the cylinder, for the purpose set forth. 95
5. In a gas or vapor motor, a cylinder of three interior diameters, one end only being closed, and a piston having three heads fitting the different diameters of the cylinder, the body of the piston between its heads being of less diameter than the cylinder portion or portions in which it works, whereby annular chambers are formed about said piston between its heads; in combination with air admission valve, a spent gas exhaust valve, and passages leading therefrom to the explosion chamber of the cylinder, a passage for conducting air admitted to said chamber to that between the forward and intermediate heads of the piston, a main admission valve in communication with the chamber last referred to, a second passage leading therefrom to the explosive chamber of the cylinder, and a check valve in said passage, substantially as and for the purpose set forth. 110
6. A gas or vapor motor comprising a cylinder provided with an annular valve controlled air passage encompassing the combustion chamber thereof, a vapor producer, and a casing for a distributing valve the inlet whereof is connected with said air passage. 130

and vapor producer respectively, in combination with a suction and forcing device adapted to simultaneously draw air from the air space and vapor from the vapor producer into the inlet of the valve casing and force the mixture into the combustion chamber of the cylinder, for the purpose set forth.

7. A hydrocarbon motor comprising a cylinder provided with air and motive fluid passages encompassing the combustion chamber thereof, and with a valve controlled exhaust and a casing for a throttle or distributing valve the inlet of which is in communication with the vapor producer and the aforesaid air space, in combination with a motor piston adapted to perform the function of suction and force plunger and draw air from said air space and vapor from the vaporizer into the throttle valve casing and force the same into the combustion chamber of the cylinder, for the purpose set forth.

8. In a hydrocarbon motor, the combination

with the piston cylinder provided with an air passage encompassing the same, an air inlet valve in communication with said passage, a 25 throttle valve connected with the latter and with the combustion chamber of said cylinder, and a vapor producer connected with the throttle valve and provided with an air inlet valve, of a piston adapted during reciprocation to draw a charge of hot air from the passage encompassing the cylinder and a charge of gas or vapor from the producer into the throttle valve and force the mixture into the combustion chamber of the cylinder, 35 and simultaneously therewith draw air into the producer, for the purpose set forth.

In witness whereof I have hereunto set my hand in presence of two witnesses.

JOHN EDWARD FRIEND.
